UNITED STATES PATENT OFFICE.

WILLIAM BECKER, OF PRIEST RIVER, IDAHO, ASSIGNOR OF ONE-HALF TO JOHN HAMBERG, OF PRIEST RIVER, IDAHO.

SAW-SETTING DEVICE.

1,188,391.

Specification of Letters Patent. Patented June 27, 1916.

Application filed March 13, 1915. Serial No. 14,244.

To all whom it may concern:

Be it known that I, WILLIAM BECKER, a citizen of the United States, residing at Priest River, in the county of Bonner and State of Idaho, have invented certain new and useful Improvements in Saw-Setting Devices, of which the following is a specification.

My invention relates to an improvement 10 in saw sets; and it consists in the peculiar construction and arrangement of parts to be hereinafter fully described, whereby a cheap, simple and effective device is produced, capable of setting saw teeth varying 15 in size at any required angle.

In describing my invention in detail reference will be had to the accompanying drawing wherein like characters denote like or corresponding parts throughout the several views, and in which:—

Figure 1 is a side elevation of my improved saw set device; Fig. 2 is an end view; Fig. 3 is a longitudinal sectional view; Fig. 4 is a detail perspective view of the base or support; Fig. 5 is a top plan view; and Fig. 6 is a detail perspective view of the retaining block or wedge.

Like numerals of reference refer to like parts in the several views.

Before proceeding with the description of the drawings I desire to call particular attention to the fact that while I have evolved my invention with particular reference to its use as a setting device for straight edge 35 saws, the same may be readily utilized, by slight modification, as a device for setting the teeth of rotary or circular saws.

Referring now to the drawings by numerals, 1 designates a suitable horizontally 40 flat base or support. Longitudinal dovetailed grooves 2—2 are formed in the said support, the grooves being open to the top face thereof and arranged in parallel relation, one groove adjacent each of the respective longitudinal edges of the support, each groove terminating at a point in spaced relation to the opposite end of the support from that where the grooves begin. An upright bearing block 3 is made integral 45 with the base or support, said block being situated at one end of the support intermediate the adjacent longitudinal edges of the grooves 2—2. Said bearing block 3 is bifurcated at its free end as indicated at 4 to 50 receive a complementary extension 5 formed

integrally with the operating lever 6 of the device, the extension 5 affording, with the bearing block 3, a means for pivotally clamping the lever 6 in a manner providing oscillatory movement by hand during a saw 60 setting operation, the point of oscillation being designated 7 in the drawings. Lever 6 is of a special design and formation, its bottom edge, throughout a portion of its length, being horizontally flat as indicated 65 at 8 to lie contiguous to the top horizontally flat surface of the base or support 1, and in actual practice, to engage the top face of the saw blade, the latter resting upon the base or support and, during a saw setting 70 operation, being movable transversely thereof in step like progress. The flat engaging face 8 of the lever 6 is equipped with an abutment block 9 of special design, the said block fitting a recess 10 therefor formed in 75 the lever, any suitable means such as a set screw 11 being provided to releasably hold the said block in place. One end of the block is enlarged to provide an inclined or angular abutting face 12, which, with a 80 complementary inclined or abutting face 13 is adapted to positively engage the saw teeth at an inclination, and to set, in this manner, the teeth at the required angle. The base or support 1 is also equipped with 85 an abutment block 14, the said block being narrowed at one end to provide the inclined abutting surface 13 aforesaid, and fitting a recess 15 therefor formed in the base, a set screw 16 being provided to releasably hold 90 said block 14 in place.

That the saw acted on may be adjusted relatively to the abutment blocks 9 and 14, and that teeth varying in size may be set without necessitating the use of different 95 abutment blocks, I provide what may be termed a gage block designated as an entirety by the numeral 17. Said gage block 17 is of a novel construction and is designed to span the upright bearing block 3, the 100 arms 18 formed by the construction noted above each terminating in an enlargement 19, the enlargements affording an abutting surface for the saw acted on. Gage block 17 may be adjusted longitudinally of the 105 base or support 1 through manipulation of a thumb screw 20 carried by the bearing block 3. To preclude movement of the said thumb screw 20 relatively to the bearing block, a dove-tailed wedge or block 21 is 110

seated in a complementary groove 22 therefore formed in the forward face of the bearing block 3. The arrangement of the thumb screw 20 and the wedge 21 is best shown in Fig. 3.

To prevent vertical displacement of the wedge block and the gage block 17 and to at all times maintain the enlargement 19 in engaging proximity with the horizontally flat top face of the base structure 4, I provide adjustable slide members 23, said members being of a dove-tailed formation in cross section and arranged to occupy the complementary grooves 2 provided therefor, said members being slidable only through manipulation of the gage block 17, the respective members being preferably cast integrally with the gage block to in this manner form a part thereof.

20 The entire device or apparatus may be fastened in any suitable manner as indicated at 24 upon a supporting structure therefor.

From the foregoing, taken in connection with the accompanying drawings it will be noted that teeth varying in size may be readily set through adjustment of the gage block 17 longitudinally of the base or support; that it is but necessary to oscillate lever 6 from the point 7 to execute a setting operation; and that abutment blocks varying in angularity and size may be utilized in lieu of the specific blocks shown to vary the pitch of the saw teeth set and to accord with teeth of unusual size.

35 In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may

be resorted to, when required, without sacrificing any of the advantages of my invention, as defined in the appended claims.

Having thus fully described my invention, what I claim as new and desire to secure by Letters Patent, is:—

1. In a saw set, a horizontally flat base structure provided with parallel dove-tailed grooves, a bearing block formed with said base structure, the block being provided with a transverse dove-tailed groove, dove-tailed slide members mounted to engage in said parallel groove, an adjustable gage block embracing said bearing block and secured to said slide members at opposite sides of the bearing block, a dove-tailed block mounted to engage in the transverse groove of the standard, a means engaging said block and said bearing block to secure adjustment of gage block, a pivoted lever, and detachable complementary saw setting devices carried by the lever and the base structure respectively.

2. In a device for setting saws, a base structure provided with spaced dove-tailed grooves, slide members fitting the respective grooves, the said members being complementary, a gage block rigid with the respective slide members, means to adjust the gage block, a bearing block integral with the base structure, a lever having pivotal connection with the bearing block, an abutment block detachable relatively to the lever, a second abutment block detachable relatively to the base structure, the said two abutment blocks being complementary, and a movable wedge block fitting a groove therefor in said bearing block for the purpose specified.

In testimony whereof I affix my signature in presence of two witnesses.

WILLIAM BECKER.
